Primary Examiner — Jennifer L Rempfer*Assistant Examiner* — Danielle Nichole Bowly(74) *Attorney, Agent, or Firm* — Venable LLP(57) **CLAIM**

The ornamental design for a printer, as shown and described.

DESCRIPTION

FIG. 1 is a front view of a printer showing my new design;
 FIG. 2 is a rear view thereof;
 FIG. 3 is a top plan view thereof;
 FIG. 4 is a bottom plan view thereof;
 FIG. 5 is a left side view thereof;
 FIG. 6 is a right side view thereof;
 FIG. 7 is a perspective view thereof;
 FIG. 8 is an enlarged view of portion A-A, B-B in FIG. 1;
 and,

FIG. 9 is an enlarged view of portion C-C, D-D in FIG. 1. The oval chain pattern is a texture pattern of the printer and is part of the claimed design, and the broken oval chain pattern is a texture pattern of the printer that forms no part of the claimed design.

The dashed broken lines shown in the drawings represent portions of the printer that form no part of the claimed design. The dot-dash broken lines show a boundary of the claimed design and form no part thereof.
